UNITED STATES PATENT OFFICE.

WALTER BUSWELL, OF BRIDGEPORT, CONNECTICUT, ASSIGNOR TO STANDARD COM-
POSITOR AKTIENGESELLSCHAFT, OF BERLIN, GERMANY.

DEVICE FOR DISTRIBUTING THE MATRICES, PATRICES, AND THE LIKE FOR TYPO-
GRAPHIC MACHINES.

Application filed February 19, 1926, Serial No. 89,482, and in Germany December 18, 1924.

This invention relates to a device for distributing the matrices, patrices and the like for typographic machines and consists essentially therein that resilient or yielding members are interposed into the point setting gear, so that any resistance to the movements of the points does not interfere with the operation of the point setting gear. More particularly, according to this invention, instead of interposing resilient or yielding members into the point setting gear, also the walls of the matrix conduits may be made resilient within the range of the switch rails, or also the latter themselves may be made resilient.

It is known to provide typographic machines with distributing devices for matrices, patrices, type and the like, in which they are distributed according to kinds and characters by a system of points and guided into the corresponding case conduits.

When in devices of this kind a matrix or the like is within the range of the points when the change over the latter has started, the points will be jammed.

The object of the present invention is to avoid this disadvantage by making the point setting gear members resilient so that the principal part of the setting gear can complete its travel even if the movement of the switch rails is more or less hindered.

Several constructions according to the invention applied to a known distributing device for matrix setting machines, is diagrammatically illustrated in the accompanying drawing. In this distributing device the matrices dropping into a common opening produce the movement of the points by feeler rods, through a series of mechanical points setting members.

Figure 1 is a partial view of the system of points,

Figure 2 a partial back view of Figure 1,

Figure 3 a section on line A—A in Figures 1 and 2,

Figures 4-10 show other constructions according to the invention.

From the receiving neck 1, the distributing conduits 2 branch downwards and they are provided in the known manner with swinging switch points 3 arranged in groups in an arc of a circle. These switch points 3 are secured to rocking spindles 4 which project through the vertical frame plate 5 and

have at their projecting rear end a driving arm 6. For each group 3, 4, 5 a swinging segment frame 7 is provided of angular cross-section, only a short portion of which is shown in Figure 2. The swinging frame 7 may be driven in the manner disclosed in the U. S. Patent to Petri-Palmedo and Goddard No. 1,171,537 of February 15, 1926. In connection with each driving arm 6, on the corresponding swinging frame 7 two spring buffers 8 are rectilinearly guided and are arranged opposite each other. The buffers clamp between them the free end of the arm 6 and during the swinging of the frame 7, they turn the arm 6 with the spindle 4 and switch point 3. If the complete movement of a switch point 3 is prevented, for instance owing to a matrix reaching this rail too late and being still within its range when the changing of the points is taking place, the pressure exercised on the point setting gear will be taken up by the spring buffers, and the spring of one buffer will be compressed, whilst the swing frame 7, together with the members of the setting gear operating it, will be able to complete its travel.

In another construction according to the invention also shown in Figure 1, the walls of the matrix conduits themselves are made resilient within the range of the points 3, for example as hinged spring controlled parts 9, or rectilinearly guided spring controlled parts 10, which are forced back in opposition to the action of their springs by the matrix which becomes jammed by the points operated.

Finally, the switch rail 3 itself can be made resilient, for instance in the form of a leaf spring. Figures 4-10 show various rails which are resilient.

I claim:

1. In a typographic machine, the combination of a distributing device for distributing the matrices, patrices and the like according to kind and character, said device comprising a point setting gear, and resilient means associated with said point setting gear, said resilient means being adapted to prevent a disturbance in the point setting gear by exerting a resistance against the switching motion thereof.

2. A typographic machine according to claim 1, having a distributing device comprising matrix conduits and a point setting

gear consisting of swinging switch points, a rocking spindle secured to each of said switch points and a frame plate, characterized in that the resilient means for the point setting gear consist of spring buffers interposed between said swinging switch point and said frame plate, substantially as described.

3. A typographic machine according to claim 1, having a distributing device comprising walls forming matrix conduits, characterized in that said walls are made movable and in that the resilient means are associated with said movable walls of said matrix conduits.

4. A typographic machine according to claims 1 and 3, characterized in that the resilient means associated with said walls of the matrix conduit consist of rectilinearly guided spring controlled parts, adapted to be forced back in opposition to the action of

their springs by a matrix which becomes jammed by the point setting gear.

5. A typographic machine according to claim 1, characterized in that the resilient means for the point setting gear form part of the distributing device.

6. A typographic machine according to claims 1 and 5, characterized in that the distributing device comprises a distributing channel, and that the resilient means are incorporated in said distributing channel by having the wall of said channel constructed as a resiliently swinging switch.

7. A typographic machine according to claims 1 and 5, characterized in that a switch rail is provided within said distributing device as a resilient wall of the latter.

In testimony whereof I have affixed my signature.

WALTER BUSWELL.
